LIQUID SPRAYER

Filed Jan. 18, 1945

UNITED STATES PATENT OFFICE

2,460,861

LIQUID SPRAYER

Harold G. Walters, United States Army,
Richmond, Ind.

Application January 18, 1945, Serial No. 573,399

3 Claims. (Cl. 299—87)

(Granted under the act of March 3, 1883, as
amended April 30, 1928; 370 O. G. 757)

1

The invention described herein, if patented, may be manufactured and used by or for the Government for governmental purposes without the payment to me of any royalty thereon.

My invention relates to sprayers operated by a hot atomizing fluid and more particularly to an improved spray nozzle so constructed that the spray liquid is heated by the atomizing fluid while these fluids are passing through the nozzle, means being provided for securing uniform heating of the spray liquid before it reaches the nozzle tip.

In sprayers of the type used in spraying insecticides, disinfectants and other liquid spray compounds the liquid is drawn through a nozzle by a motivating or atomizing fluid such as steam, air or water which is ejected from an aspirating outlet in the gun at high velocity and at that point strikes the spray liquid at high velocity and in such a manner that it is atomized and intimately mixed with the atomizing fluid discharging from the nozzle of the gun.

In the spraying of many insecticides and disinfectants, it has been found that heating of the compound before it reaches the nozzle tip assists greatly in securing a more finely atomized spray. Although various types of nozzles can be found in the prior art and some of these could be adapted for heating the spray compound as it passes through the nozzle, yet none are effective to provide the degree and uniformity of heating desired in the spraying of insecticide and disinfectants. It is therefore an object of this invention to provide a new and improved sprayer in which a maximum and uniform heating of the spraying compound is secured while it is passing through the spray nozzle.

Another object of the invention is the provision of a new and improved sprayer in which a maximum heating of the spraying compound is secured from the hot atomizing fluid.

Another object of the invention is the provision of a new and improved sprayer having means for agitating the spray fluid in its passage to the nozzle tip to effect more uniform heating of the liquid, the agitating means also acting as a heat exchange element to increase the heating of the fluid.

Another object of the invention is the provision of a new and improved sprayer which is durable and compact in construction and inexpensive to manufacture so that it may be permanently installed at very little cost in locations where relatively frequent spraying is necessary.

Another object of the invention is the provision of a spray nozzle in which the atomizing fluid surrounds a spray liquid delivery conduit and is caused to flow in a tortuous path about the conduit to provide maximum contact between the hot atomizing fluid and conduit and more effective heating of the conduit and fluid therein.

2

Another object of the invention is the provision of the new and improved sprayer having a heat exchange element secured about the spray fluid supply conduit in the nozzle to provide more effective heating of the fluid in the conduit by the atomizing agent.

Although the embodiment which I have described for the purpose of illustrating the invention is a preferred form, it will be obvious as the 10 description proceeds that changes in the form and arrangement of parts may be made without departing from the scope and spirit of the invention. In the drawings Figure 1 is a fragmentary view partly in section showing my sprayer permanently secured to a support such as the wall of a room.

Figure 2 is a horizontal section of the spray nozzle of my device.

Figure 3 is a cross-sectional view taken on the 20 line 3—3 of Figure 2.

Figure 4 is a cross-sectional view taken on the line 4—4 of Figure 2.

Referring to Figure 1, the sprayer includes a spray nozzle assembly 10, a reservoir 11 for containing the liquid spray compound, a tube 12 for delivering spray compound from the reservoir to the spray nozzle and a bracket 13 secured to the top of the reservoir for supporting the nozzle in operative position and for securing the entire 30 assembly to the wall of a room or any other permanent support.

The nozzle 10 includes a combined heat exchange element and liquid spray supply conduit 14, machined from brass or other suitable metal 35 or made from a casting machined on certain surfaces to provide a close fit with the inner surface of a tubular housing 15 which incloses the heat exchange element 14. A separate cap 16 is provided for closing the forward end of the housing.

40 The heat exchange element 14 comprises an elongated tubular body 17 extending longitudinally in the housing 15. It is provided with an annular flange 18 on its rear end machined on its outer surface to fit snugly in the rear end of the housing and with a reduced end 19 which extends 45 forwardly from the tubular portion and forms the nozzle tip. The heat exchange element 14 and its flange 18 are provided with an axial bore 20 forming a conduit or passageway of large cross-section 50 for liquid insecticide which terminates in a conically shaped forward end 21 communicating at its apex with a greatly reduced bore 22 extending through the reduced end 19 of the said heating element to form the discharge outlet therefor.

55 Disposed upon the enlarged tubular portion of the heat exchange element 14 are a plurality of spaced slotted fins 23 which are concentric therewith and are machined on their outer surfaces 24 to provide a snug fit with the inner surface 25 of the housing 15. Radial slots 26 are formed in

each of these fins to provide a passageway for the flow of steam through the housing and to the cap 16, the slots on adjacent fins being diametrically opposed as shown in Figures 3 and 4 so that the atomizing fluid in passing from the space between two fins to the succeeding space strikes the side of the succeeding fin and must flow around the heat exchange element 14 to reach the slot in that fin. It will be obvious that by forcing the hot atomizing fluid to flow in a zigzag path that the contact between the atomizing fluid and the fins and heat exchange element is increased so that more effective heating of both is secured. The fins 25 present a large contact surface to the hot atomizing fluid and thus are adapted to absorb large quantities of heat therefrom which in turn is conducted to the heat exchange element 14 further increasing the heating thereof and of the spray liquid passing therethrough.

Housed within the heat exchange element 14 is a helical coil spring 27 which abuts against the forward end 21 of the axial bore 20 of the said element and is held in position by the inner end of an elbow fitting 28 secured in the threaded outer end of the bore 20. This fitting is secured to the spray delivery tube 12 by a coupling 29. A screen 30 may be interposed between the delivery tube 12 and the fitting 28 to prevent the passage of impurities which may be present in the spray compound into the bore 20. The coils of the spring 27 are in contact with the walls of the bore 20 and absorb heat therefrom so that the spring acts not only as an agitator of the spray liquid flowing through the bore, but also as a heat exchanger for imparting additional heat to the fluid.

The combined heat exchange element and tubular supply conduit 14 are enclosed by the tubular housing 15 and the conical shaped hollow cap 16 which has a base 31 and an apex 32 provided with an aperture 33 extending through the cap. The base of the cap 16 has a reduced portion 34 adapted to be received in the forward end of the housing 15 in snug engagement therewith, and an annular shoulder 35 against which the forward end of the housing 15 abuts when the cap is in position in the housing. The reduced tip 19 of the heat exchange element 14 extends through the aperture 33 in the cap 16 and terminates in the plane of the outer edge of this opening which is of slightly larger diameter than the tip, providing an annular passageway 36 of small cross-sectional area between the tip and the interior of the cap. Both of these parts are machined to accurately define the area of this passageway and provide an aspirating outlet for the nozzle.

To assemble the parts, the cap 16 is arranged in position with its base 31 abutting against the foremost fin 23 on the heat exchange element 14 and the tubular housing 15 is pressed over the heating element and reduced portion 34 of cap to hold the parts in assembled relation. If desired the seams between the cap and the housing and the flange 18 and the housing may be sealed by brazing or soldering to assure a leakproof union between these parts so that steam or other atomizing fluid cannot escape through these seams.

An inlet to the space within the housing is secured through a cylindrical boss or fitting 37 which is permanently secured to the outer surface of the housing at its rear end and has an aperture 38 extending axially therethrough and registering with an aperture 39 in the housing 15. The aperture 38 in the boss is threaded from its outer end for a portion of its length and receives the threaded tip 40 of a conduit 41 for supplying

atomizing fluid under pressure. The inner face of the boss is concave in form to correspond to the outer surface of the housing and is secured to the housing by brazing or welding or by any other suitable means which will provide a leakproof union between the housing and boss.

Any container of appropriate size may be used as a reservoir for spray liquid, but I have found that an ordinary glass Mason jar makes a very suitable reservoir in those installations where the sprayer is to be permanently secured in a room. Such jars are provided with a metallic cap 42 which is threaded onto the neck of the jar and has a flat top surface which forms an ideal base to which the horizontally extending arm 43 of the bracket 13 may be secured by means of a rivet 45 or any other suitable means. In assembled relation the forward end of the nozzle 10 is supported on the vertically extending arm 44 of the bracket as shown in Figure 1 and may be secured thereto in any suitable fashion to hold the nozzle securely in position. With the nozzle mounted in the position described, and shown in Figure 1, the spray delivery tube 12 projects upwardly from the reservoir through an aperture 46 in the edge of the cap and a coinciding aperture 47 in the horizontal arm of the bracket 13. In order to provide a rigid assembly the spray delivery tube 12 may be welded or soldered to the cap 42 and bracket 13 after the correct positioning thereof has been secured.

A downwardly extending arm 48 is also provided on the bracket and may be secured to the wall of a room or to any other suitable means for permanently mounting the sprayer in a room. If it is desired to fill the reservoir 11 when the sprayer is so mounted, it is unscrewed from the cap 42 and lowered until the top edge of the reservoir clears the lower end of the delivery tube 12 which extends into the reservoir to a point near its bottom. When filled it is screwed back into the cap and the sprayer is then ready for use.

Although not limited to such use, the sprayer described herein is particularly suitable for installation in exterminator systems for various types of rooms that require frequent spraying such as storage rooms for furs and other products that are attacked by insects or it may be used to advantage in buildings for human occupancy which are located in areas infested with disease bearing insects such as malaria mosquitoes. When it is desired to spray a room, the nozzle is connected to a source of steam having a pressure of from 30 to 50 pounds per square inch by the flexible hose 41 having the tip 40 which is threaded into the boss 37. A manually operated valve which is not shown may be provided in the hose for regulating the pressure of the steam and thereby determining the rate of operation. In this manner it is possible to thoroughly spray a room of about 25,000 cubic feet capacity in 5 or 6 minutes using a single sprayer.

Steam from the hose 41 enters the space in the jacket 15 between the flange 18 and the first fin 23 through the fitting 37 and the aperture 39 in the housing and passes from this space through the slot 26 in the top of the first fin to the space between the first and second fin and from there through the slot 26 in the lower part of the second fin and in this zigzag fashion through the jacket until it emerges through the slot 26 in the forward fin 23 into the cap 16. In this manner maximum contact between the steam and the heat exchange element and the most effective heating of the spray liquid is secured so that it

is at a high temperature when it reaches the tip 19. Escape from the cap is limited to the annular passageway 36 between the tubular tip 19 and the edges of the opening 33. Because of the relatively reduced cross-sectional area of passageway 36 the velocity of the steam as it escapes is increased to an extent sufficient to create and maintain a vacuum at the end of the tubular tip as long as steam flows through the nozzle. This vacuum causes the insecticide to be aspirated from the reservoir through the delivery tube 12 bore 20 and reduced bore 22 to the tip. As it leaves the tip it is struck with great force by escaping steam causing it to be atomized and intimately mixed with the steam.

While I have described a sprayer particularly adaptable for use in spraying insecticide which must be heated prior to ejection from a nozzle to secure the best atomization using steam as a motivating and atomizing fluid, it will be obvious that my spray nozzle is suitable for use with other types of spray compounds which normally exist in liquid form, and that fluids other than steam for example hot water or hot air may be used in operating these sprayers. Spray nozzles are commonly used in oil burners to vaporize the viscous liquid fuel used in such burners and my nozzle could readily be adapted for use in oil burners where it would be particularly effective in cold weather because fuel oil tends to become more viscous at such times. Other applications of my device will suggest themselves, particularly where it becomes necessary to atomize a viscous material which is more readily atomized at elevated temperatures. The embodiment shown and described is intended merely to exemplify one form of my invention and I do not desire to have it limited thereby except insofar as it is limited by the appended claims.

I claim:

1. A liquid atomizing device comprising (1) a conduit communicating with a liquid reservoir, said conduit having an elongated straight tubular wall of large cross-section for the conveyance of said liquid, (2) spiral means coaxial with and interiorly of said conduit and in heat exchange relation with the tubular wall of said conduit for agitating and heating the liquid conveyed through said conduit, (3) a tubular outlet of small cross-section communicating with said conduit, (4) an elongated tubular housing for the conveyance of atomizing fluid under pressure, said housing surrounding said conduit and communicating with a source of supply of said atomizing fluid, (5) said housing having a constricted outlet portion surrounding said first-named outlet and terminating in the same plane as said first-named outlet in aspirating relation therewith, and (6) heat conductive means exteriorly on said conduit and extending into said housing for defining a path of flow for said atomizing fluid through said housing to said aspirating outlet from side to side of the housing and around said conduit to effect maximum contact between said atomizing fluid and said conduit and to obtain optimum heating thereof and of the liquid passing through said conduit.

2. A liquid atomizing device comprising (1) a conduit communicating with a liquid reservoir, said conduit having an elongated straight tubular wall of large cross-section for the conveyance of said liquid, (2) a coil spring coaxial with and interiorly of said conduit and in heat exchange relation with the tubular wall of said conduit for agitating and heating the liquid con-

veyed through said conduit, (3) a tubular outlet of small cross-section communicating with said conduit, (4) an elongated tubular housing for the conveyance of atomizing fluid under pressure, said housing surrounding said conduit and communicating with a source of supply of said atomizing fluid, (5) said housing having a constricted outlet portion surrounding said first-named outlet and terminating in the same plane as said first-named outlet in aspirating relation therewith, and (6) a plurality of spaced heat-conductive fins exteriorly on said conduit and extending into said housing, said fins being slotted alternately at diametrically opposite points for defining a zigzag path of flow for said atomizing fluid through said housing to said aspirating outlet from side to side of the housing and around said conduit to effect maximum contact between said atomizing fluid and said conduit and to obtain optimum heating thereof and of the liquid passing through said conduit.

3. A liquid atomizing device comprising (1) a liquid reservoir, (2) a conduit communicating with said liquid reservoir, said conduit having an elongated straight tubular wall of large cross-section for the conveyance of said liquid, (3) spiral means coaxial with and interiorly of said conduit and in heat exchange relation with the tubular wall of said conduit for agitating and heating the liquid conveyed through said conduit, (4) a tubular outlet of small cross-section communicating with said conduit, (5) an elongated tubular housing for the conveyance of atomizing fluid under pressure, said housing surrounding said conduit and communicating with a source of supply of said atomizing fluid, (6) said housing having a constricted outlet portion surrounding said first-named outlet and terminating in the same plane as said first-named outlet in aspirating relation therewith, (7) heat-conductive means exteriorly on said conduit and extending into said housing for defining a path of flow for said atomizing fluid through said housing to said aspirating outlet from side to side of the housing and around said conduit to effect maximum contact between said atomizing fluid and said conduit and to obtain optimum heating thereof and of the liquid passing through said conduit, and (8) a supporting element secured to said reservoir, said supporting element having an arm at one end for supporting said housing in operative position and an arm on the opposite end for securing said device to a permanent support in a permanent location.
